(57) CLAIM

The ornamental design for a spray gun, as shown and described.

DESCRIPTION

FIG. 1 is a first perspective view of a spray gun showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG.

2.

The broken lines shown in the drawings depict portions of the spray gun that form no part of the claimed design. The long dash-short dash broken line circles in FIG. 2 and FIG. 9 define the bounds of the enlargements and do not form part of the claimed design.
